UNITED STATES PATENT OFFICE

162,375

EMBOSSED EMBROIDERED FABRIC

George Brandon, New York, N. Y.

Application June 23, 1950, Serial No. 10,700

Term of patent 3½ years

(Cl. D3—9)

To all whom it may concern:

Be it known that I, George Brandon, a citizen of the United States of America, residing in New York city, county of New York, and State of New York, have invented a new, original, and ornamental Design for an Embossed Embroidered Fabric, of which the following is a specification, reference being had to the accompanying drawing, forming part thereof, wherein, the figure is a plan view of an embossed embroidered fabric showing my new design.

I claim:

The ornamental design for an embossed embroidered fabric, substantially as shown.

GEORGE BRANDON.
